UNITED STATES PATENT OFFICE

134,473

DESIGN FOR A FIRE ALARM BOX FRONT PANEL

Martin Dorman, Baltimore, Md.

Application March 16, 1942, Serial No. 106,203

Term of patent 14 years

To all whom it may concern:

Be it known that I, Martin Dorman, a citizen of the United States and a resident of the city of Baltimore and State of Maryland, have invented a new, original, and ornamental Design for a Fire Alarm Box Front Panel, of which the following is a specification, reference being had to the accompanying drawing, forming part thereof.

Figure 1 is a front elevational view of a fire alarm box front panel showing my new design;

Figure 2 is a side elevational view of the article shown in Figure 1.

Figure 3 is a top plan view thereof, and

Figure 4 is a central vertical sectional view thereof.

The dominant features of my design reside in the portions shown in full lines.

I claim:

The ornamental design for a fire alarm box front panel, as shown and described.

MARTIN DORMAN.
